UNITED STATES PATENT OFFICE.

ALEXANDER GIRTANNER, OF NEW YORK, N. Y., AND ROBERT H. MILLER, OF ST. LOUIS, MISSOURI, ASSIGNEES TO AMERICAN STEAM CONVEYOR CORPORATION, OF CHICAGO, ILLINOIS, A CORPORATION OF NEW YORK.

SECTIONAL ELBOW FOR ASH-CONVEYERS.

1,289,154.

Specification of Letters Patent. Patented Dec. 31, 1918.

Original application filed April 29, 1915, Serial No. 24,628. Divided and this application filed February 12, 1917. Serial No. 148,103.

To all whom it may concern:

Be it known that we, ALEXANDER GIRTANNER and ROBERT H. MILLER, citizens of the United States, residing, respectively, at New York, in the county of New York, and State of New York, and city of St. Louis, in the State of Missouri, have invented a certain new and useful Improvement in Sectional Elbows for Ash-Conveyers, of which the following is a full, clear, concise, and exact description, reference being had to the accompanying drawings, forming a part of this specification.

Our invention relates to conveyer systems such as are used for conveying ashes; our present invention being particularly concerned with the construction of an improved sectional elbow which is adapted to form a part of the conduit of such an ash conveyer system.

This application is divisional of our co-pending application Serial No. 24628, filed April 29, 1915.

In the accompanying drawings illustrating our invention,

Figure 1 is a more or less diagrammatic representation of an ash conveyer system embodying the improvements of our invention.

Fig. 2 is a vertical sectional view of the sectional elbow to which our present invention is particularly directed, and

Fig. 3 illustrates the elbow in rear elevation.

Similar characters of reference refer to similar parts throughout the several views.

Referring first to Fig. 1, at 10 we have illustrated the vertical portion of the conveyer conduit. This vertical portion 10 is secured by any suitable fastening means 11, to a wall or other support illustrated at 12, it being understood that portion 10 of the conduit, which is shown broken away, leads to any suitable discharge point such as an ash hopper. The lower portion of the vertical part 10 of the conduit is conveniently supported by up-rights 13, engaging with collar 14, encircling the conduit, as shown. The lower end of the vertical portion 10 of the conduit is connected to the horizontal portion 15 through an elbow indicated as a whole by reference numeral 16. The

elbow 16 is illustrated in more detail in Figs. 2 and 3. The elbow consists essentially of the curved inner portion 17, back 18 and the bottom 19. The back 18 and the bottom 19 are substantially straight and are secured to the curved inner portion 17 by means of lugs 20 and bolts 21, as is clearly illustrated in the several views. The bottom 19 of the elbow has secured in it a removable jet 22 which is supplied with steam from any suitable source through a pipe 23. The bottom 19 and back 18 are conformed to provide an opening in which is inserted a wear plate 24. The wear plate 24 is held in position by a spring bar 25, engaging with lugs 26 on the back and bottom sections of the elbow. While the bottom 19 is substantially straight in its conformation, it has on its inner surface an inclined guiding face 29 for delivering ashes toward the steam jet at an angle. The face of the wear plate 24 is also preferably inclined to assist in guiding the ashes into the vertical portion 10 of the conduit.

The elbow 16, the details of which have just been described, connects the vertical part 10 of the conduit with the horizontal part 15, which we may state is provided with a hopper 27, booster jet 28, etc. Our present invention is, however, not particularly concerned with any part of the ash conveyer system except the elbow, illustrated in detail in Figs. 2 and 3. In so far as the other features of the system are concerned, it will suffice to say that they are fully illustrated, described and explained in our co-pending application hereinbefore referred to.

It will be seen that the elbow hereinbefore described is particularly adapted for use in steam jet ash conveyer systems for the reason that any one of the several parts of the elbow may readily be renewed if the same becomes worn. The wear plate 24 which receives the greatest amount of wear is readily removable and may be removed or replaced without disturbing the other parts of the elbow. Moreover, the back and bottom of the elbow may readily be removed without disturbing the other parts of the elbow or pipe line.

Having thus described our invention what

we claim is new and desire to secure by Letters Patent of the United States is:

1. An elbow for ash conveyers comprising a curved inner portion, a removable bottom and a removable back, said back and bottom being substantially straight.
2. An elbow for ash conveyers comprising a curved inner portion, a removable bottom and a removable back, said bottom overlapping said back.
3. An elbow for ash conveyers comprising a curved inner portion, a removable bottom and a removable back, said bottom overlapping said back having an opening extending therethrough.
4. An elbow for ash conveyers comprising a curved inner portion, a removable bottom, a removable back and a removable wear plate arranged in an opening in said bottom and back.
5. An elbow for ash conveyers comprising a curved inner portion, a removable bottom, a removable back, provided with an opening and an inclined guiding face adjacent to said opening.
6. An elbow for ash conveyers comprising a curved inner portion, a substantially

straight bottom and a substantially straight back, said bottom and back being removable and connected to said curved inner portion in planes at right angles to one another.

7. An elbow for ash conveyers comprising a curved inner portion, a substantially straight bottom and a substantially straight back, said bottom and back being removable connected to said curved inner portion in planes at right angles to one another, and said bottom overlapping said back and joined thereto in the plane of the joint between said bottom and said curved inner portion.

In witness whereof, we hereunto subscribe our names this 24 day of January, A. D. 1917, and this 31st day of January, A. D. 1917, respectively.

ALEXANDER GIRTANNER.
